UNITED STATES PATENT OFFICE.

WALTER K. SMITH, OF ELLWOOD CITY, PENNSYLVANIA.

TENT.

1,342,234.

Specification of Letters Patent. Patented June 1, 1920.

Application filed October 11, 1919. Serial No. 329,967.

To all whom it may concern:

Be it known that I, WALTER K. SMITH, a citizen of the United States, and resident of Ellwood City, in the county of Lawrence 5 and State of Pennsylvania, have invented a new and useful Improvement in Tents; and I do hereby declare the following to be a full, clear, and exact description thereof.

My invention relates to tents, and it has 10 special reference to tents of the type having a straight ridge, from which the tent is adapted to be suspended by means of a rope or other non-rigid support, as distinguished from the usual solid ridge pole.

15 The object of my invention is to provide a tent of the class described in which sagging of the top of the tent will be substantially prevented.

In the accompanying drawing, Figure 1 20 is a perspective view of a tent constructed in accordance with one form of my invention; Fig. 2 is a longitudinal vertical sectional view taken at the ridge of the tent shown in Fig. 1, the supporting rope being 25 shown as extending through the ridge construction, but not drawn taut; Fig. 3 is a longitudinal sectional view similar to Fig. 2, but showing the supporting rope in its taut or supporting position; Fig. 4 is a 30 transverse vertical sectional view of the ridge construction shown in Fig. 1; and Fig. 5 is a perspective view of a modified form of ridge construction.

When tents having straight ridge-pole 35 constructions, such as the ordinary A-tents and wall tents, are to be transported and used at frequent intervals, it is often desirable to dispense with the usual supporting poles and ridge poles, and to suspend the 40 tents from ropes stretched between trees or other convenient supports. However, it is difficult, if not impossible, to maintain a supporting rope of this kind in a perfectly horizontal position, and the resultant sagging 45 of the top of the tent is objectionable, not only because of its unsightly appearance, but also on account of the lessened resistance to wind and water presented by a loose and sagging tent.

50 According to my present invention, I have produced a tent which may be suspended from a rope or other non-rigid support and in which the top of the tent is maintained horizontal in spite of the necessary sagging 55 of the supporting rope. To these ends, I provide the tent with a ridge-piece consist-

ing of a loop of fabric extending lengthwise of the tent ridge, the ridge-piece or loop being provided with means for conforming to the curvature of the supporting 60 rope without distortion of the body of the tent. The ridge-piece may consist of a strip of canvas secured to the sides of the tent, or it may be formed from the sides of the tent themselves, as will more clearly be de- 65 scribed below.

Referring to Figs. 1 to 4, inclusive, of the drawing, the tent 1 is shown, for the purpose of illustration, as an ordinary wall tent provided with guy ropes 2 and suspended from a rope 3, the ends of which may be attached to trees or other convenient supports. A ridge-piece 4 extends lengthwise of the ridge of the tent and defines a space 5 for receiving the supporting rope 3. 75 In this modification of my invention, the ridge-piece 4 consists of a strip of canvas, or other fabric, cut with its two longer edges curved inwardly. When the strip is attached to the sides of the tent, by stitching or otherwise, the longer edges of the strip are stretched until they are substantially straight, as shown in Fig. 1, the result being that the space 5 defined by the ridge-piece 4 is deeper at the ends of the tent than 80 in the middle.

Fig. 2 shows the relation of the above-described parts at the time when the rope 3 is passed through the loop or ridge-piece 4, and before the rope is drawn taut. Here 90 the top of the tent is shown as sagging somewhat, while the top of the loop 4 is curved to a greater degree. When the rope 3 is drawn taut, the parts assume the position shown in Fig. 3, the top 6 of the tent 95 1 being horizontal, while the loop or ridge-piece 4 conforms to the curvature of the rope 3. There is thus no sagging of the tent proper, and, therefore, no wrinkling of the sides of the tent. If desired, the ends of 100 the ridge-piece 4 may be provided with cords 7 or other attaching means for preventing the tent from slipping lengthwise upon the rope 3.

Fig. 5 shows a modified form of tent constructed in accordance with my invention, this form being preferred where it is desired to dispense with even the small amount of curvature present at the top of the ridge-piece, described above and shown in Fig. 1. 110 In the modification of Fig. 5, the ridge-piece 4 is shown integral with the sides of

the tent 1, and is formed by stitching the sides of the tent together, as shown at 8. Obviously, the ridge-piece 4, in this modification, may, if desired, consist of a separate piece attached to the tent as in Fig. 1. The depth of the loop formed by the ridge piece 4 should be sufficient to receive a curved portion of the rope 3 without distortion of the canvas. In order to provide 10 a bearing surface for the supporting rope, the sides of the loop 4 are secured together by means of eyelets 9 or the like, these eyelets being so disposed that a line connecting them conforms to the curve produced by 15 the ropes 3 when the rope is stretched to a convenient degree of tightness. Instead of the eyelets 9, other means may be employed for securing the sides of the ridge-piece 4 together at intervals, and if desired, 20 such attaching means may be replaced by one or more curved rows of stitching following the path to be occupied by the supporting rope 3.

Other modifications in the construction 25 and arrangement of parts may readily be made by those skilled in the art without departing from the spirit of my invention, and I therefore desire that no limitations be imposed upon my invention, except such 30 as are indicated in the appended claims.

I claim as my invention:

1. A tent having a ridge construction extending substantially the full length of the tent adapted for suspension from a non-rigid support and also adapted to prevent substantial sagging of the ridge when the tent is in use.

2. A tent having a substantially straight

ridge and provided with means disposed above the said ridge and extending substantially the full length thereof for suspending the tent from a non-rigid and non-rectilinear support.

3. A tent provided with a loop of fabric extending from end to end of the ridge thereof, the said loop being adapted for suspension from a curved rope or the like while maintaining the ridge of the tent substantially straight.

4. A tent provided with a loop of fabric 50 extending lengthwise of the tent at the ridge thereof, the said loop being adapted to receive a rope or other support and being deeper at its ends than in the middle.

5. A tent provided with a ridge-piece of 55 fabric secured to the sides of the tent at the ridge thereof, the said ridge-piece forming a space lengthwise of the tent for receiving a rope or other support the said space being deeper at its ends than in the 60 middle.

6. A ridge construction for tents comprising a strip of fabric cut with its two longer edges curved inwardly, said strip being secured to the sides of the tent at the 65 ridge thereof with its originally curved edges substantially straight, whereby the said strip defines a space lengthwise of the ridge of the tent, the said space being deeper at its ends than in the middle.

In testimony whereof, I the said WALTER K. SMITH, have hereunto set my hand.

WALTER K. SMITH.
